Sam'l Gardiner Jr.

UNITED STATES PATENT OFFICE.

SAMUEL GARDINER, JR., OF NEW YORK, N. Y.

IMPROVEMENT IN GAS-BURNERS.

Specification forming part of Letters Patent No. 78,871, dated June 16, 1868.

To all whom it may concern:

Be it known that I, SAMUEL GARDINER, Jr., of New York city, and county of New York, in the State of New York, have invented a certain new and useful Improved Self-Lighting Gas-Burner; and I do hereby declare the following to be a full, clear, and exact description of the same, reference being had to the accompanying drawings, which form a part of this specification.

My invention consists, first, in combining a platinum coil or its equivalent with a gas-burner in such a manner that it will effect the combustion of a slight leak of gas and retain sufficient heat to reignite the gas if blown out; second, in the combination of a hood or cap with a platinum coil or its equivalent applied within said hood or cap.

In the drawings, Figure 1 is a perspective view of a gas-burner illustrating my invention. Fig. 2 represents an axial section of the same. Fig. 3 represents an axial section in a plane at right angles to Fig. 2.

A is the burner proper, the tip *a* of which is formed by preference of lava or analogous non-corrosive substance, and may have the customary "fish-tail" or any other suitable jets.

B represents a hood or cap slotted at top for the passage of the flat flame, and perforated at *b b* for the admission of air to aid combustion. Within the upper end of the hood I place a coil, *c*, of platinum wire or any other metallic or any other body of suitable character and construction to adapt it when once heated by the flame to retain and communicate sufficient heat to reignite the gas after it has been extinguished.

In order the more effectually to retain the heat in the platinum coil *c* or its equivalent, I

prefer to form the key *D* with a very small groove, *d*, so as when the main supply of gas is turned off to permit a slight escape of gas, which will burn in an invisible flame in contact with the coil. The result is that after the gas has been turned off for an indefinite period, when it is again turned on the gas by coming in contact with the hot platinum coil will almost instantly reheat it to redness, and thereby will be ignited.

The invention is also very valuable in causing the instant relighting of the gas in the event of it being extinguished by wind, or from any cause by ignorance, carelessness, or accident, without being turned off.

The cap or hood *B*, by causing a forced current of heated air and concentrating it in contact with the gas, causes the more perfect combustion of the latter and increases the intensity of the light.

The employment of the non-corrosive tip is of manifest advantage where a small flame is kept constantly burning.

Having thus described my invention, the following is what I claim as new and desire to secure by Letters Patent:

1. The combination of the coil *c* with a key, *D*, formed with one or more notches, apertures, or grooves, as at *d*, so as to permit a slight leakage of gas when the main supply is turned off, as shown and described.
2. The combination of the coil *c* or its equivalent with the hood or cap *B*, substantially as and for the purposes specified.

SAML. GARDINER, JR.
